UNITED STATES PATENT OFFICE.

CHARLE OLSON, OF JAMESTOWN, NEW YORK.

DESIGN FOR A COMBINATION PINCUSHION, SPOOL RACK, AND BUTTON HOLDER.

Application filed July 6, 1925. Serial No. 13,997. Term of patent 14 years.

To all whom it may concern:

Be it known that I, CHARLE OLSON, a citizen of United States of America, residing at Jamestown, in the county of Chautauqua and State of New York, have invented a new, original, and ornamental Design for Combination Pincushion, Spool Rack, and Button Holder, of which the following is a specification, reference being had to the accompanying drawing, forming part thereof.

The figure is a perspective view of a combination pincushion, spool rack, and button holder, showing my new design.

I claim:

The ornamental design for a combination pincushion, spool rack, and button holder, as shown.

In testimony whereof I affix my signature.

CHARLE OLSON.
